UNITED STATES PATENT OFFICE.

HENRY PENNIE, OF BROOKLYN, NEW YORK, ASSIGNOR OF ONE-HALF TO
LOUIS C. SCHLEIP, OF SAME PLACE.

INSULATOR FOR SUPPORTING AND HOLDING ELECTRIC WIRES.

SPECIFICATION forming part of Letters Patent No. 359,812, dated March 22, 1887.

Application filed April 14, 1886. Serial No. 198,755. (No model.)

To all whom it may concern:

Be it known that I, HENRY PENNIE, a citizen of the United States, residing at the city of Brooklyn, in the county of Kings and State 5 of New York, have invented certain new and useful Improvements in Insulators for Supporting and Holding Electric Wires, of which the following is a specification.

My invention relates, chiefly, to insulators 10 for holding and supporting electric wires; and its object is to provide an insulator of simple construction, which will not only support an electric wire, but also avoid the necessity of securing the electric wire to the insulator by 15 tying with additional pieces of wire, and thereby make a saving of time, labor, and material.

By the use of my invention a desirable means 20 of introducing and holding electric wires in buildings is also provided, whereby the danger 25 of fire and grounding of the wires is lessened and obviated.

In the accompanying drawings similar letters of reference designate corresponding parts in all the figures.

25 Figure 1 represents a top view of one form of my improved insulator. Fig. 2 represents a sectional view at *xx* of Fig. 1. Fig. 3 represents a longitudinal section in detail.

30 A designates the core or body of the insulator, made of porcelain, glass, or other suitable non-conducting material, having a longitudinal slot, B, of peculiar form, extending through the same. The walls or sides *aa* of this slot extend parallel downward for a short 35 distance and then diverge outward at an angle, as shown by *bb*. The bottom *ee* of the slot has a semicircular depression or cavity, C, extending along its length, in which an electric wire, D, is placed by inserting the same 40 between the space formed by the walls *aa*, which is of sufficient width to admit the wire. This cavity or depression C is preferably of such a size and depth as to cover and protect about two-thirds of the circumference of the 45 wire D.

A tapering wedge, E, made of hard rubber or other suitable non-conducting composition or material, corresponding in shape to the spaces in the lower part of the longitudinal 50 slot B, formed by the sides *bb* and the bottom

ee, is inserted at one end of the opening in the lower end of the slot formed by said sides *bb*, and is forced or drawn tightly therein, and is secured thereto by means of a cap or pin, *c*, or other suitable devices.

55 It will be seen that the wedge E bites upon the wire D at its exposed portion and firmly holds it in the cavity C of the core A, and by reason of the peculiar construction of the lower part of the slot B a key or cork-wedge 60 hold is obtained, which securely locks the wire in place and prevents its moving or being pulled out at either end.

As will be seen in Figs. 2 and 3, the core or body A is provided with a hole, V, extending 65 at right angles to the opening in the slot B, and part of which hole is made large enough for the head of a screw, P, to pass in and be secured some distance below the wire D.

The insulator may be provided with a series 70 of slots, or a series of depressions in the cavity of the slot, of the construction set forth for holding a number of wires, and instead of having a single screw, P, as in Figs. 2 and 3, a number may be used. Two wedges may be 75 used instead of a single one, E, and be inserted at each opening of the slot B, and they will securely hold the wire D without pins *c*.

The shape of the body or core A of the insulator may also be made of different forms, 80 as desired.

Where the portion of the insulator to be annexed to a wall is flat, as Y in Figs. 2 and 3, a coating or padding, *o*, of rubber or textile fabric or material, may be secured to the flat 85 surface Y by adhesive material, which will prevent the insulator chipping or breaking when tightly screwed to a wall or pole, and at the same time provide an additional non-conducting material.

90 By the use of my invention it will be seen that electric wires introduced in buildings may be mounted and held in position without additional tying or coming in contact with any part of the building itself, and danger from 95 ignition from the wires, as also the grounding of the electricity by the wires touching conducting material, be entirely avoided.

I am aware that lightning-rod insulators have been made with a central opening and 100

open back, and closed by means of a wedge-shape or taper filling-piece having a flanged head fitting in a recess in the top of the core to prevent its dropping out, the opening and filling-piece being dovetailed to prevent the latter from being removed laterally from the back of the insulator, and such improvements I do not here claim.

What I claim as my invention, and desire to secure by Letters Patent, is—

The insulator A, having a slot, B, with par-

allel and divergent sides *a a b b*, with a depression, C, in the bottom *e e* of the cavity formed by said sides *b b*, and provided with a hole or holes, V, substantially as set forth.

In testimony whereof I have hereunto subscribed my name this 13th day of April, 1886.

HENRY PENNIE.
